UNITED STATES PATENT OFFICE.

JOHN DI GAUDIO, OF BROOKLYN, NEW YORK.

DESIGN FOR A LIGHTING-FIXTURE WALL BRACKET OR ARTICLE OF ANALOGOUS NATURE.

Application filed April 30, 1929. Serial No. 31,057. Term of patent 3½ years.

To all whom it may concern:

Be it known that I, JOHN DI GAUDIO, a citizen of the United States of America, and a resident of Brooklyn, county of Kings, and State of New York, have invented a new, original, and ornamental Design for a Lighting-Fixture Wall Bracket or Article of Analogous Nature, of which the following is a specification, reference being had to the accompanying drawing, forming a part hereof.

In the drawing:

Figure 1 is a front view of the lighting

fixture wall bracket or article of analogous nature, the part shown in full line outline being ornamented in the same manner as the part more fully illustrated; and

Figure 2 is a diagrammatic side outline view of the same.

I claim:

The ornamental design for a lighting-fixture wall bracket or article of analogous nature, substantially as shown and described.

JOHN DI GAUDIO.
